LEVER ACTUATED PIVOTED OUTER JAW
WRENCH WITH PIVOTED BACK CATCH

Hervey W. Small, Dubois, Idaho

Application March 31, 1949, Serial No. 84,695

1 Claim. (Cl. 81—81)

1

This invention relates to wrenches, and more particularly, has reference to a wrench of improved design capable of use as a pipe wrench and for similar functions.

An important object of the present invention is to provide a wrench of generally improved design, that will be capable of swift preliminary adjustment of the jaws to the object to be gripped.

Another important object is to provide a wrench having an improved jaw retraction means, whereby the jaws can be disengaged from the gripped object swiftly and with ease.

With the foregoing and other objects in view which will appear as the description proceeds, the invention consists of certain novel details of construction and combinations of parts, herein-after more fully described and pointed out in the claim, it being understood that changes may be made in the construction and arrangement of parts without departing from the spirit of the invention as claimed.

Referring to the drawings.

Figure 1 is a view in side elevation of a wrench constructed in accordance with the invention.

Figure 2 is a top plan view.

Figure 3 is a longitudinal section.

Figure 4 is an enlarged detail section on line 4—4 of Figure 1.

Figure 5 is an enlarged section on line 5—5 of Figure 1.

Figure 6 is an enlarged section on line 6—6 of Figure 1.

Figure 7 is a view partly in side elevation and partly in longitudinal section through a modified form.

Referring to the drawings in detail, the reference numeral 5 designates a channeled body integral at one end with the rearwardly extended elongated channeled handle 6. Pivotally connected to the forward end of the channeled body 5 is the outer or stationary jaw 7, the pivotal connection of the jaw 7 to the body 5 being designated 8.

A channeled lever 9 underlies and straddles the body 5 and its integral handle 6, said channeled lever 9 including the spaced parallel extensions 10 that extend forwardly along opposite sides of the body 5. A cross pin 11 connects the jaw 7 to the front end of the channeled lever 9, and the channeled lever is pivotally connected to the body 5 by means of the pivot pin 8. Since jaw 7 is connected to the channeled lever 9, or more properly its forward extensions 10, at two places, by the pins 8 and 11 respectively, it is seen that the lever 9 and jaw 7 swing as one on the pivot 8.

2

An elongated bar 13 is embraced by and slides longitudinally of the handle 6, said bar 13 having at its rear end the elongated longitudinal closed slot 14. A pull back spring 15 extends longitudinally of the slot 14, and is connected at one end by a cross pin 16 to the handle 6, and at the other end is hooked through an opening 17 formed in the bar 13. Thus, means is provided for retracting the bar 13 within the handle 6, when said bar 13 is freed for retraction in the following manner. Teeth 18 are formed on the bar 13.

However, a latch 19 is mounted in the body 5, being pivotally mounted within the body as at 20 and having extended from one end the latch handle 21. At the other end, the latch 19 is formed with teeth 22 complementary to the teeth 18 of the bar 13.

Means are provided to yieldably urge the latch into toothed engagement with the bar 13, this means comprising a spring 23 coiled around a guide pin 24 having at one end the open slot 25 in which is received the transversely extended pin 26 that is mounted in the body 5. The other end of the guide pin is extended into the front end of the latch 19 for the purpose of holding said latch in toothed engagement with the bar 13.

Extended transversely through the slot 14 is the stop pin 27 adapted to limit relative movement between the handle 6 and the bar 13.

At its front end, the bar 13 is formed with a yoke 28 between the arms of which extend the pin 29, that passes through ears 30 that extend rearwardly from the toothed jaw member 31. Jaw member 31 is thus secured rigidly to the front end of the bar 13.

The operation of the invention as shown in Figures 1 through 6 inclusive may not be noted. Assuming that the bar 13 has been fully retracted, one is able to adjust the jaw 31 toward the jaw 7 by grasping the handle 6 with one hand and grasping the lever 9 in the other hand. Lever 9 is then pulled away from the handle 6. This causes a portion of the lever 9 designated at 31' in Figure 1 to engage the ears 30 whereupon continued movement of the lever 9 away from the handle 6 will cause the jaw 31 and bar 13 to be moved to the left in Figures 1 to 3 inclusive, toward the jaw 7. The position of the jaw 31 shown in the drawings is its maximum advanced position.

The jaw 31 is moved forwardly or to the left in the drawings as much as desired to effect a rough preliminary adjustment of the two jaws against the member to be gripped, not shown. Adjusted positions of the jaw 31 are defined by

the teeth 22 and the longitudinal series of teeth 22 can be of any reasonable length for the purpose of permitting adjustment within a wide range. The adjustment of said jaw 31, of course, is against the action of the spring 15.

The jaw 31 will be held in a position to which adjusted by means of the latch 19, which will be urged against teeth 22 by means of the spring 23.

The wrench is now ready for use, and having been adjusted against the member to be gripped, the user can with one hand compress lever 9 against the handle 6, thereby pivotally swinging jaw 7 closer to the jaw 31 and tightly gripping the pipe or other object gripped. The movement of the lever 9 against the handle 6 is against the action of the spring 12. Accordingly, assuming that the pipe or similar object has been rotated as desired, one need only release the lever 9, whereupon spring 12 secured to said lever and engaging the under side of the handle 6 will cause relative movement of the handle 6 and lever away from each other, thus to spring the jaws 7 and 31 apart and releasing the gripped object. If it is now desired to retract the jaw 31, the user simply presses the lever handle 21, whereupon the pull-back spring 15 retracts the jaw 31 to its maximum extent in which the ears 30 engage the lever 9 at 31'.

Considering the form of the invention illustrated in Figure 7, a handle or body 32 has pivotally connected as at 33 the pivoted jaw 34. A bar 35 is toothed as in the previous form of the device, and slides longitudinally of and within the handle 32, being normally retracted by means of a pull-back spring as in accordance with the first form of the invention. At its front end, the bar 35 is equipped with the jaw 36.

Jaws 34, 36 are normally sprung apart by means of a spring arrangement which differs somewhat from the arrangement of the first form of the invention. To this end, I recess the bar 35 as at 37, to receive a compression spring 38, which engages the jaw 34 and presses it away from the jaw 36. I do not provide in the form of the invention illustrated in Figure 7 a lever such as the lever 9. However, I do provide a latching means that has toothed engagement with the teeth of the bar 35 as in the first form of the invention.

In the use of the invention as illustrated in Figure 7, the forward adjustment of the jaw 36 is provided for simply by pressing to the left in Figure 7 the rear end of the toothed bar 35, shown projecting from the handle 32 at the right of Figure 7. The toothed bar 35 ratchets along 55 the locking lever or latch as in the first form of the invention, and will be retained in any position to which adjusted. The wrench is then used in the regular manner, and whenever released, will spring away from the gripped object under 60

the action of the spring 38. When full use has been made of the wrench shown in Figure 7, the jaw 36 is retracted in the same manner as the jaw 31 in the first form of the invention, that is, by depression of the latch handle.

Swinging movement of the jaw 34 away from the jaw 36 under the action of the spring 38 is limited by flat portion 39 formed on said jaw 34.

What is claimed is:

10 A wrench comprising an elongated handle, a jaw member pivotally connected to the handle for movement in an arcuate path adjacent one end of the handle, a jaw carried by the jaw member for movement in an arcuate path remote 15 from the handle from an active position in which it extends substantially perpendicular to the longitudinal axis of the handle to an inactive position in which it lies at an angle to one side of the handle, a lever pivotally connected to the handle and connected to the jaw member for moving it in its arcuate path, a bar member mounted in the handle to move longitudinally through the end of the handle adjacent the jaw member, a second jaw carried by the bar member to move therewith in a rectilinear path toward and away from the handle adjacent the end thereof carrying the jaw member, yielding means connected between the handle and bar member for moving the second jaw toward the handle, rack teeth carried by the bar member, and a toothed latch bar pivoted on the handle for engaging the rack teeth and holding the bar member in a selected position and against movement by the yielding means, and cam means carried by the lever for engaging the second jaw and moving it toward the jaw member against the effort of the yielding means.
